UNITED STATES PATENT OFFICE.

JOSEPH JURAN, OF NEW YORK, N. Y.

DESIGN FOR A MUFF.

SPECIFICATION forming part of Design No. 22,828, dated October 10, 1893.

Application filed August 15, 1893. Serial No. 483,226. Term of patent 3½ years.

To all whom it may concern:

Be it known that I, JOSEPH JURAN, a subject of the Emperor of Austria-Hungary, at present residing in the city, county, and State

5 of New York, have invented a new and original Design for a Muff, of which the following is a specification, reference being had to the accompanying drawing, forming part thereof.

The figure is a perspective view of a muff 10 showing my design.

The leading feature of my design is the cover, A, of the muff, having scattered, orna-

mental, elongated figures of irregular outline, the circular bands of trimming, B, at the ends of the muff, and the curved band, or trimming 15 C, which connects them.

I claim—

The design for a muff, as herein shown and described.

JOSEPH JURAN.
